AIR MOVING DEVICE

Raymond C. Troy, Cedar Rapids, Iowa

Application July 1, 1949, Serial No. 102,565

4 Claims. (Cl. 230—258)

1

This invention relates to air moving devices or fans and has particular relation to means for operating devices of that nature from a vacuum line or from a source of air under low pressure such as a domestic type vacuum cleaner.

It is a primary object of my invention to provide a new and novel arrangement and combination of an air-circulating fan powered by means such as the conventional domestic vacuum cleaner.

Another primary object of my invention is to provide means by which the owner of a conventional type of vacuum cleaner may employ such device to power an air-circulating fan.

A further object of the invention is the provision of an air-circulating fan and motive power therefor by means of which the conventional motor drive may, if desired, be eliminated from a room so as to eliminate the heat as well as the noise normally resulting from the use of an electric motor drive within a closed room.

Another main object of my invention is to provide novel means whereby an air-operated motor, normally employed for other purposes and powered by means such as a vacuum cleaner, may be quickly arranged and converted to drive an air-circulating fan.

A still further object of my invention is to provide a novel means for circulating air within a room which will, at the same time, induce a gradual change of air within the room.

Other and further features and objects of the invention will be more apparent to those skilled in the art upon a consideration of the accompanying drawings and following specification, wherein are disclosed exemplary embodiments of the invention, with the understanding, however, that such changes may be made therein as fall within the scope of the appended claims, without departing from the spirit of the invention.

In the drawings:

Figure 1 is a view in perspective illustrating a preferred embodiment of my invention.

Figure 2 is a view, partly in elevation and partly in longitudinal vertical section of a device constructed in accordance with my invention.

Figure 3 is a vertical cross section taken along the line 3—3 of the device shown in Figure 2.

Figure 4 is a fragmentary view in perspective, illustrating, in exploded relation, the elements of an exemplary means for detachably mounting the fan blades on the air-motor of Figures 1, 2, and 3, and

Figure 5 is a view partly in side elevation and partly in vertical section illustrating a modified form of my invention.

Referring now to these drawings and, in particular, to Figure 1 thereof in which an air-motor or turbine, indicated generally at 10, is supported in a cradle-like base or stand 11 and connected by means of a conduit or hose 12 to the vacuum cleaner 13, the connection being made to the suction side of the cleaner in the case of the air motor shown. A fan assembly 14 is detachably mounted on the output shaft 15 as will be described hereinafter.

As best illustrated in Figures 2 and 3, the air-motor 10 comprises a flattened, two-part, generally oval-shaped case 16, the rear portion 161 of the case being secured to the forward or gear-case portion 162 by means of screws, not shown. A turbine wheel 17, located in a cylindrical recess 163 of the casing, is supported by the shaft 18 which is, in turn, mounted for free rotation in the bearing 19. A spur gear 21 on the forward end of shaft 18 is meshed with the larger gear 22 so as to drive the output shaft 23 at reduced speed, the output shaft and large gear 22 being mounted for free rotation on the stub shaft 24. The gear 22 is retained in position by means of a thrust washer 26 and enclosing shield 27.

Air drawn from the discharge opening 164 and through the conduit 12, by means of the vacuum cleaner 13, enters the air motor 10 through the grilles intake opening 165 and is directed by the vanes 166 against the turbine blades 171 to thus cause rotation of the turbine wheel, the structure and design of the air motor being generally in accordance with common practice.

The output shaft 23 carries a driving plate 28 including a sleeve 29, to the outer end of which a flanged disc 31 is secured. This driving plate, best shown in Figures 2 and 4, is provided with helical slots 32 in the sleeve portion 29 to receive studs 33 which are threaded into the output shaft. The helical slots are so arranged that rotation of the output shaft 23 tends to wind the driving plate inwardly toward the housing, such movement, however, being resisted by tension springs 35 secured between studs 33 and projections 40 on the rear of the drive plate. The purpose of this structure has no bearing in the present application.

The disc 31 is provided with a pair of spaced guide holes 34 and a pair of radially extending slots 36, the holes being adapted for the reception of guide pins 37 secured to the inner surface of the fan assembly mounting plate 38. This mounting plate is preferably recessed as at 39 for a snug fit over the drive plate 28, the outer

edge of the plate having a plurality of curved fan blades 41 riveted thereto.

Latch members 42 are mounted for radially slideable movement on the face of the mounting plate by means of guide slots 43 and rivets 44 as well as the hook-shaped portions 46 extending rearwardly through radial guide slots 47 in the plate. These latch members 42 are adapted to be forced inwardly toward one another, against the pressure of the leaf springs 48, so as to permit the hook portions 46 to enter the slots 36 in the driving plate 28. Release of pressure on the ends of the latch members permits the pressure of the springs 48 to engage the hooks to the driving plate at the outer ends of the slots 36 and thus secure the fan assembly in position.

A cylindrical plug 49 or the like is secured to the rear surface of the mounting plate 38 centrally thereof and, when positioned in the outer end of the drive-plate sleeve 29, this member abuts the end of the output shaft 23 and prevents longitudinal motion of the sleeve relative to the output shaft.

A hub-cap 51, generally dome-like in shape, is flanged as at 52 for frictional engagement over the central portion of the mounting plate 38, portions of the flange 52 being cut away as at 53 to permit extension therethrough of the outer ends of the latch members 42.

The base 11 comprises a hollow, flat-bottomed portion 54 and a generally elliptical cradle 56 adapted to receive the bottom portion of the air-motor housing. An arm 57, projecting rearwardly from the base is slotted vertically at its outer end as at 58 to receive a thumb screw 59, said screw comprising a part of the hose clamp 61.

In the modified form of my invention illustrated in Figure 5, the fan housing 70 has a forward or cover portion 71 having an elongated bearing portion 72 supporting the turbine shaft 73. A fan 74 is mounted on the outer end of the shaft and a turbine-wheel 76 mounted on the inner end thereof. The rear housing member 77 is secured by screws 78 to the cover member and has a cylindrical recess 75 enclosing the peripheral portion of the turbine wheel except for the air-inlet opening 79 in which vanes 81 serve to direct air against the turbine blades 82 in a manner similar to that illustrated by Figure 3.

Air drawn through the turbine is removed through the discharge opening 83 and the hollow standard 84 which member is mounted in a socket 86 in the base 87. An outlet connection 88 in the base and thimble 89 provide for attachment of the vacuum hose 12.

I have shown and described herein a new and novel combination and arrangement of elements providing means for circulating air within a room or the like and utilizing a conventional vacuum cleaner as a source of power. The air motor or turbine employed to drive the fan blades, in one embodiment of the invention, is a type commonly employed in conjunction with such a vacuum cleaner for driving a floor waxing brush and one of the important features of my invention lies in the novel means provided for adapting such a device to an entirely different use.

Devices embodying my inventive idea have numerous important advantages. In addition to the advantage of lowered cost, such an air moving device may be employed when quiet operation is desired, as in sickrooms, in which case the vacuum cleaner itself may be placed in another room. Further advantages, when the device is 75

employed in this manner, are continuous replacement of a portion of the room air and elimination of the heat of the electric motor from the room.

Although I have described specific embodiments of my invention, it is apparent that modifications thereof may be made by those skilled in the art. Such modifications may be made without departing from the spirit and scope of the invention as set forth in the appended claims.

I claim as my invention:

1. In a device of the character described for use in conjunction with a vacuum cleaner; a casing, an air turbine therein having an output shaft projecting from one side of the casing, a base member having a cradle-like portion adapted to receive the lower end of the casing, means for securing the casing in said cradle-like portion, hose means connecting the air turbine and the vacuum cleaner, a disc-like drive plate mounted on the output shaft and having radially elongated apertures therein, a detachable mounting plate also having radially elongated apertures therein, latching members having hook-like portions projecting through the apertures in both of said plates, means for aligning the mounting plate with the drive plate, means biasing said latching members into latching engagement with the drive plate, and fan blades secured to the mounting plate.

2. For use in combination with a vacuum cleaner and an air turbine of the class described and having a circular, radially-slotted drive plate mounted on the output shaft of the turbine; a generally circular mounting plate having fan blades mounted thereon and having a portion thereof recessed for reception over the drive plate, the mounting plate also having radially extending slots therein aligned with the slots in the drive plate, latching members having hooked portions thereof extending through said slots in both plates, spring means biasing said hooked latching means into position latching said plates together and spacing means extending rearwardly from the center of the mounting plate and adapted to bear against the end of the output shaft.

3. For use in combination with a vacuum cleaner and an air turbine of the class described having an apertured drive plate mounted on the output shaft thereof; a generally circular mounting plate having fan blades attached thereto, projections extending rearwardly from the plate and engageable in the apertures of the drive plate for aligning and driving the mounting plate, and latch means mounted on the mounting plate and having portions thereof engageable with the drive plate for securing said plates together.

4. For use in combination with a vacuum cleaner and an air turbine of the class described having an apertured drive plate mounted on the output shaft thereof; a generally circular mounting plate having fan blades attached thereto, projections extending rearwardly from the plate and engageable in the apertures of the drive plate for aligning and driving the mounting plate, latch means mounted on the mounting plate and having portions thereof engageable with the drive plate for securing said plates together and spacer means extending rearwardly from the mounting plate and abutting the end of the output shaft.
